UNITED STATES PATENT OFFICE

JOHN DASENBROCK AND JOSEPH A. CRAGAN, OF POUGHKEEPSIE, NEW YORK

GUARD ATTACHMENT FOR WRINGERS

Application filed August 31, 1932. Serial No. 631,144.

This invention relates to an attachment for clothes wringers, and the primary object of the invention is to provide a guard for the power driven clothes wringers of washing machines, which is so designed that the easy feeding of the clothes in between the wringer rolls is permitted but the possibility of the operator's fingers being caught in the rolls is prevented.

10 Another object of the invention is to provide a guard in the form of a simple, durable and cheap attachment that can be mounted upon any of the well known power wringers.

15 A further object is to provide means in a guard of this kind, whereby the clothes may be readily fed to the rollers in such a manner that it will be impossible for the fingers of the operator to become engaged or caught by the rollers, and also to provide means whereby the sides of the device are also protected in such a manner that a child can not reach the rollers through the sides of the guard, as is now the case with other 25 devices intended for this purpose.

Another object of the invention is to provide means whereby the sight feed of the clothes between the wringer rolls is not obstructed in any manner, and yet the roll-pass is fully protected and can not be reached by the hands except for cleaning or clearing the rolls.

With these and other objects in view, our invention consists in certain novel construction and combination of parts as will hereinafter be fully described and claimed in the annexed specification, and fully illustrated in the accompanying drawing in which like figures of reference refer to corresponding parts in all of the views, but we do not confine ourselves to the exact design as shown as slight changes may be made without departing from the spirit of the invention.

In the drawing—

Figure 1 is a top plan view of a power wringer, showing the device attached to one side thereof, the other side showing partly in section.

Figure 2 is a side elevation of the device,

showing the same as attached to a power wringer.

Figure 3 shows an enlarged partial view of a corner of the guard plate, to illustrate the method of locking the same to the frame.

Figure 4 shows a partial inside view of one of the side frames, with the wringer rolls in section, and the conveyor belt in place, with a bunch of clothes passing under one of the idler rolls upon the belt to the wringer rolls.

Figure 5 shows an end elevation of the device as applied to a power wringer.

Figure 6 shows a partial enlarged view of one of the upper corners of the guard plate, illustrating the method of mounting the same to the side frame.

Referring to the drawing—

We have herewith indicated the usual type of power driven wringer, comprising the roller supporting posts 10, within which are rotatably mounted the wringer rolls 11 which are rotated in opposite directions by the power driven gear box 13 which is mounted upon one of the posts 10.

The wringer is also provided with the usual roll adjusting means 14 and 15, and supplied with the drip pan 16.

Our guard attachment comprises the two side frames 17 which are connected at one end by the channel shaped member 18 which embraces one of the supporting posts 10, as shown in Figures 2, and 5; the other side frames 19 are also connected together by a channel member 20 which embraces the other supporting post 10; this member 20 being provided with the ears 21 to which is bolted the gear box 13 by the bolts 22, thus attaching the guard frames to the wringer in a detachable manner.

The guard side frames 17 and 19 are formed with a wing or closed portion 23 to prevent access to the wringer rollers 11 from the side and any danger of the operator's fingers coming into contact with the rollers from the side.

The guard sides 17 and 19 are also formed with an arm integral therewith and projecting therefrom at an angle thereto, and in the outer ends of these arms 24 are formed

slotted bearings 25 within which are adjustably secured by the nuts 26 the ends of a threaded shaft 27 upon which is mounted in a freely rotatable manner a roller 28 of 5 some suitable material such as rubber and which is slightly crowned in the center.

Adjacent the junction of the arm 24 and the wing 23 is formed alined bearings 29 within which are freely mounted the ends 10 of the shafts 30 which carry the idler rolls 31, which may also be of rubber or other suitable material; while adjacent the upper part of the wings 23 are the bearings 32 within which are mounted the trunnions 33 15 which carry the hinged guard plate 34.

Around the rollers 28 and between the power wringer rollers 10 is passed an endless belt or conveyor 35 which is made of rubber or other suitable resilient material 20 that has a considerable amount of stretch; this belt 35 passing under and normally in contact with the idler rollers 31, but due to its elongating qualities allowing the clothes 36 to pass between the belt 35 and the roller 25 31.

The idler roller 31 being mounted on the same plane as the center of the power wringer roller 10, and thus below the roll-pass, the fingers of the operator while in 30 the act of feeding the clothes upon the belt 35 and under the roller 31 can not in any manner reach the roll-pass; and the clothes passing upon the conveyor belt 35 and in contact with the idler roller 31 are partly 35 pressed before reaching the wringer rollers 10.

For effecting a guard for the roll-pass and at the same time not affecting the sight feed of the clothes to the roll-pass, and also for 40 preventing any clothes from passing around the roller 31 and not entering the roll-pass, we have provided a guard plate 34 comprising a frame within which is mounted a glass 37; said frame 34 being provided with a pair 45 of trunnions 33 by which it is hinged at the top to the side frames 17 and 19, while at its lower edge it is provided with two latches 38 by which it is locked in place to the side frames in such a manner that it may be 50 raised for cleaning the wringer rollers 10 and removing any clothes that may become clogged between the rollers 10; and at the same time it will prevent any clothes from 55 passing around the roller 31 and act as a guide to the roll-pass.

Having thus described our invention, what we claim as new and desire to secure by Letters Patent, is—

A guard attachment for power clothes 60 wringers, comprising in combination with wringer supporting posts and rollers, of side frames formed with a channel portion to embrace said supporting posts and detachably secured thereto, arms formed on 65 said side frames and projecting below the

lower wringer roll, rollers mounted in said arms, idler rollers mounted in said frames above said rollers and below the roll-pass of the wringer rollers, an endless resilient conveyor belt mounted on said rollers and passing 70 between said roll-pass and in contact with the idler rollers, and a guard plate mounted in said side frames above the idler rollers and adjacent the roll-pass.

In testimony whereof, we affix our signatures.

JOHN DASENBROCK.
JOSEPH A. CRAGAN.
